(57) **CLAIM**

The ornamental design for a spotting telescope alignment lock.

DESCRIPTION

The invention described here may be made, used and licensed by and for the U.S. Government for U.S. Governmental purposes.

FIG. 1 is an isometric view of the alignment lock.

FIG. 2 is a front elevation view of the alignment lock.

FIG. 3 is a right side elevation view of the alignment lock.

FIG. 4 is a left side elevation view of the alignment lock.

FIG. 5 is a rear view of the alignment lock.

FIG. 6 is a bottom view of the alignment lock; and,

FIG. 7 is a top view of the alignment lock.
